Attorney.

UNITED STATES PATENT OFFICE

HOWARD C. BAILEY, OF LOS ANGELES, CALIFORNIA, ASSIGNOR, BY MESNE ASSIGNMENTS, TO RICHARD W. TULL, OF FANWOOD, NEW JERSEY

TABLE TOP

Application filed November 16, 1925. Serial No. 69,354.

This invention particularly pertains to a table which is especially adapted for use in cafeterias, self-serving restaurants, lunch rooms and the like, where it is customary for the patrons to carry their purchases to tables on trays, and has as its primary object the provision of a table which is so formed as to compel a diner to employ a predetermined portion of the table top area and thereby avoiding encroachment upon table space allotted to other diners occupying the same table; in other words, necessitating a diner placing his table ware within a confined or a predetermined area or space.

15 A further object is to provide a table in which the top structure is of open construction, and the table top surface proper formed by placing a removable tray thereon whereby the use of a tray as a support for table ware is necessitated, and the transfer by the customer of his purchases from his tray to the table prevented, thereby obviating the accumulation of dishes, silver ware and the like, on the table top and facilitating removal 25 thereof.

Another object is to provide a table top of the above character with associated trays embodying constructions and arrangements whereby a tray may be supported on the table top and occupy only a predetermined portion thereof.

With the foregoing objects in view together with such other objects and advantages as may subsequently appear, the invention resides generally in forming a table top member of open construction and in the provision of a tray of such size and configuration that it will occupy only a certain portion 35 of the table top, and in fitting the table top frame with a means for supporting a plurality of such trays together with means for holding the trays against lateral displacement or possible tipping.

40 The invention further resides in the parts, and in the construction, combination and arrangement of parts hereinafter described and claimed and illustrated by way of example, in the accompanying drawing, in which:—

45 Fig. 1 is a perspective view of a table top

showing the invention as applied to a circular table;

Fig. 2 is a perspective view of a tray adapted to be employed with the table shown in Fig. 1;

Fig. 3 is a perspective view illustrating a table top as equipped with a plurality of trays, portions being broken away;

Fig. 4 is an enlarged detail and vertical section as seen on line 4—4 of Fig. 3, showing 55 the manner in which the trays are supported on the table top and maintained in allotted places thereon;

Fig. 5 is a perspective view illustrating the application of the invention to a rectangular 60 table top.

Referring to the drawings more specifically, 6 indicates generally a table top structure or frame which embodies a marginal rim portion 7 and a series of spaced slats 8 extending 65 interiorly of the rim 7, and arranged to form supports for demountable trays 9. In the application of the invention shown in Figs. 1 and 3, the rim 7 is of annular form and the slats 8 project interiorly from its 70 inner periphery radially thereof, while in the form shown in Fig. 5 the rim 7 is of rectangular shape with the slats 8 extending 75 parallel to each other. The table top structure is thus formed of open frame construction, of such character as to preclude placing 80 of table ware, such as dishes, silver ware, etc. thereon.

In carrying out the invention the table 85 structure may be formed of any desired shape and may be made of any suitable material, and it may be supported in any appropriate fashion.

The trays 9 are formed of such size and shape that a plurality of the trays arranged 90 side by side and resting on the table top frame structure 6, will substantially cover the structure and form the top surface thereof, and are so proportioned relative to the area and the space bounded by the rim 7 that 95 only a definite number of the trays may be placed upon the table top structure at any one time. In the case of the table top structure being of circular formation the trays 9 are formed of generally segmental form as 100

particularly shown in Figs. 2 and 3 with their forwarded arcuate edges adapted to substantially conform to the outer margin of the rim 7 and with their convergent side margins extending radially and formed with upturned flanges 10; and where the table top structure is of rectangular form as shown in Fig. 5, the trays 9 will be of general rectangular shape with their side or rear margins formed with upturned flanges.

As a means for affording an allotted space on the table top structure to receive a tray, upstanding capped pins 11 are provided on certain of the slats 8 to project alongside 15 the side margins of a tray, as particularly shown in Fig. 4, to limit transverse or lateral shifting of a tray positioned on the table top structure between a set of pins. These capped pins in addition serve as guides 20 to facilitate positioning of the trays on the table top structure and provide projections which will insure disposing the trays in their proper positions as they would act to tilt a tray in event the latter be disposed to rest 25 on the pins. The extension heads or caps on pins prevent possible tipping of the tray forward when heavy pressure is applied to the outside edge thereof. These anti-tipping devices are adapted to engage contiguous trays, 30 when the latter are seated on the table.

It will now be seen that by reason of the openings provided in the table top structure between the spaced slats 8, it cannot be used 35 to support table ware unless the latter is first placed upon a tray, thus compelling the diner to keep his table ware within the confines of his tray and within a definite portion of the table top structure and serves to facilitate removal of the used table ware, as the table 40 may be cleared by merely removing the tray with its contents. The use of the invention also obviates the cleaning off the table after it is used by a diner; and on removal of a tray with its contents, insures a clean and inviting 45 place for a succeeding diner to dispose of his tray.

It will be understood that in the use of the invention the table top structure is normally trayless, the trays being supplied the customer with his order and then carried to the table and placed thereon to be afterward removed with its contents to place the table in readiness for use by a succeeding diner.

While I have shown and described a 55 specific embodiment of my invention, I do not limit myself to the exact details of construction and arrangement shown, as in carrying out the invention, various forms of tables and trays may be employed, as occasion 60 may require. For example, the tables may be oval or semi-circular or may be formed of various numbers of angular side portions, such for example, as hexagonal, octagonal, triangular or in the form of a wall, shelf or table, and the trays formed of suit-

able shape in outline to adapt them to the spaces or divisions provided on the table top structure to receive them, and accordingly, the foregoing description is to be considered as explanatory and not in any limiting sense. 70

What I claim and desire to secure by Letters Patent is:

1. A table top comprising a plurality of trays each having an upstanding marginal flange and a body having plane upper and lower faces, a support, for the table top, constructed of openwork, and devices upstanding from the openwork for dividing its area to receive only a predetermined number of the trays of the table top, there being an 80 unobstructed space above said trays when they are supported upon said table top to adapt the table for diner's use. 85

2. A rigid table top provided with apertures of sufficient size to preclude supporting table ware directly thereon, said apertures not being of sufficient size to preclude support of eating trays, and a plurality of eating trays adapted to be supported on said table top, there being an unobstructed space above said trays when the latter are in the place to permit use thereof for eating purposes, portions of the table top between said apertures being adapted safely to support and prevent lateral movement of contiguous 95 trays. 100

In testimony whereof, I have affixed my signature.

HOWARD C. BAILEY.
